UNITED STATES PATENT OFFICE.

FEDOR SZEWCUK, OF FLINT, MICHIGAN.

FLOOR-CLEANING MACHINE.

1,283,355.

Specification of Letters Patent. Patented Oct. 29, 1918.

Application filed June 26, 1918. Serial No. 241,929.

To all whom it may concern:

Be it known that I, FEDOR SZEWCUK, a subject of the Emperor of Austria, residing at Flint, county of Genesee, and State of Michigan, have invented certain new and useful Improvements in Floor-Cleaning Machines, of which the following is a specification.

This invention relates to improvements in devices for cleaning floors, and has as its special object the provision of an apparatus which may be rolled over the surface to be swept, the apparatus containing a rotary brush adapted for manual operation whereby the dirt and accumulations are gathered and delivered into a compartment from whence they may be readily removed.

A further object is to provide means whereby the brush may be raised or lowered relatively to the surface over which the apparatus moves, thereby providing for wear and also permitting it to be applied in a manner not possible to attain in devices in which the brush is rotatably mounted in fixed bearings.

These and other like objects are attained by the novel construction and combination of parts hereinafter described and shown in the accompanying drawings, forming a material part of this disclosure, and in which:

Figure 1 is a front elevational view, showing a scrubbing machine made in accordance with the invention.

Fig. 2 is a side elevational view of the same.

Fig. 3 is a vertical sectional view, taken on line 3—3 of Fig. 1, and

Fig. 4 is a fragmentary vertical sectional view taken on line 4—4 of Fig. 2.

The device comprises a hollow, arcuately curved casing 10, with which are engaged end plates 11, the casing being mounted upon pairs of rollers 12, fixed to spindles 14, engaged in the end plates 11, the rear spindle 14 passing through a compartment 15, the outer wall 16 of which is integral with the casing 10, while the inner wall 17 acts as a partition, which in conjunction with the upwardly turned bottom plate 18, forms a compartment for the accumulations, as they are swept over the apron plate 19 by the brush.

Arranged over the plate 17 are a pair of hinges 20 by which is engaged a lid or cover

21, provided with a knob 22, having attached 55 at its inner end a latch or button 23, engageable with the adjacent edge of the casing 10, the arrangement being such that the cover 21 may be held in engagement with the casing.

Secured centrally to the end plates 11 are a pair of columns 25, having between them a connecting cross-bar 26, and a top bar 27 so that the columns are firmly secured together, and journaled in the column is a 65 shaft 30, arranged with collars 31 upon each end, the extending shaft being formed into a crank 32, provided with operating handle 33.

Mounted on the shaft 30 is a bevel gear 35, 70 in engagement with a bevel pinion 36, affixed upon the end of a vertical shaft 38, journaled in a bracket 39, and also in the cross-bar 26. This shaft is preferably tubular and adapted to receive the reduced end 40 of another shaft 41, forming a continuation of the shaft 38, in which the reduced end 40 enters telescopically and is rotatably engaged by the key 42, the lower end of the shaft 41, extending downward into the casing 10, and passing revolvably through a transverse bar 44, the ends of which are slidably engaged within slots 45, formed longitudinally in the lower portion of the columns 25, so as to move freely therein.

Secured to the lower side of the bar 44 are brackets 46, and rotatably mounted in the brackets is a shaft 48, its ends extending within the slots 45 so as to be guided by the same.

Rigidly mounted upon the shaft 48 is a cylindrical brush 50, the same being contained between the brackets 46, while beyond one of the brackets is a miter gear 51 meshing with another miter gear 52, fixed 95 upon the lower end of the shaft 41.

Thus, as the handle 33 is rotated, rotary motion is conveyed through the telescopic shafts and gears to the brush 50, causing it to rotate.

Affixed in the movable cross-bar 44 is a bolt 54, a similar bolt 56 extending downward from the cross-bar 26, the threaded portions of the bolts being engaged with a turn buckle 55, whereby the bar 44 and shaft 105 48, together with the brush secured upon it, may be raised or lowered relative to the cross bar 26, and obviously maintained at an

adjusted distance from the level surface over which the apparatus operates, such adjustment being permitted by the telescopic shafts by which rotary motion is conveyed 5 to the brush.

From the foregoing it will be seen that when the brush is caused to rotate, the sweepings are delivered upon the apron plate 19, and then into the compartment over 10 the curved plate 18, from which they can be removed by opening the cover 21 in an obvious manner.

Having thus described my invention what I claim as new and desire to secure by Letters Patent, is—

1. In a floor cleaner, the combination with a casing, and a pair of columns arising therefrom, of a shaft journalized horizontally in said columns, means for rotating said 20 shaft, a vertical shaft formed in sections, the lower section being telescopically engaged in the upper sections, gearing connecting between said horizontal and vertical shafts, a transverse bar movable vertically within recesses in said columns, brackets extending below said bar, a shaft mounted in said brackets, a rotary brush affixed upon said shaft, and gear connections 25 between said shaft and the lowermost section of said vertical shaft whereby rotary motion may be communicated to said brush, and means for raising and lowering said

bar and brush with respect to the surface over which the apparatus moves.

2. In a floor cleaning machine, the combination with a casing, pairs of rollers in the front and rear thereof, and a brush rotatably mounted therein, of a compartment for receiving dust in said casing, a plate covering the entrance to said compartment, a pair 40 of columns rising from the sides of said casing, cross bars engaging between said columns, a shaft journalized in said columns, a vertical shaft formed of telescopic sections, gear connections between said vertical shaft, and the first named shaft, a gear connection between the lowermost section of telescopic shaft and said brush whereby it may be rotated, slots formed longitudinally in the lower ends of said columns, a bar slidably 45 engaged in said slots, a threaded rod engaged in said bar extending upwardly, a corresponding threaded rod engaged in one of said cross-bars extending downwardly in alignment with the first named rod, a turn-buckle engaging the threaded ends of said rods, whereby said brush may be raised or lowered, and means for rotating the first named shaft whereby rotary motion may be communicated to said brush.

In testimony whereof I have affixed my signature.

FEDOR SZEWCZUK.
